WILLIS A. SCHLEIT, OF SYRACUSE, NEW YORK.

DRAFT-REGULATOR FOR HOT-WATER HEATERS.

1,026,965

Specification of Letters Patent.

Patented May 21, 1912.

Application filed June 26, 1911. Serial No. 635,420.

To all whom it may concern:

Be it known that I, WILLIS A. SCHLEIT, of Syracuse, in the county of Onondaga, in the State of New York, have invented new and useful Improvements in Draft-Regulators for Hot-Water Heaters, of which the following, taken in connection with the accompanying drawings, is a full, clear, and exact description.

10 This invention relates to certain improvements in draft regulators for hot water heaters for any purpose where it is desired to maintain a substantially uniform degree of temperature and incidentally to prevent 15 excessive waste of fuel. It is particularly useful in connection with hot water heating systems for incubators, brooders, green houses, drying rooms and other inclosures in which a close regulation of temperature is 20 required, and while it is especially adapted for upright hot water boilers in which the check and draft ports communicate with each other above the fire box, or combustion chamber, it may be used in connection with other 25 forms of boilers or stoves having water containers associated therewith.

The primary object is to utilize the expansion and contraction of the water under varying degrees of heat for regulating the 30 combustion in the heater. In other words I have sought to provide simple and efficient means for operating the draft and check valves or dampers of the boiler through the medium of a float resting in or upon a 35 column of heated water connected to the circulating system.

Other objects and uses relating to specific parts of the draft regulating mechanism will be brought out in the following description.

40 In the drawings—Figure 1 is a front elevation of a boiler and part of a hot water circulating system connected thereto, showing a water column or expansion tank in section and the exposed portions of the means 45 for regulating the operation of the check and draft dampers or valves of the boiler. Figs. 2 and 3 are enlarged sectional views of the upper portion of the boiler, showing the check and draft valves and operating 50 means therefor, Fig. 2 showing the check

valve open and the draft valve closed while Fig. 3 shows the check valve closed and the draft valve open.

In order that my invention may be clearly understood, I have shown an upright boiler 55 —1— as provided with a fire box or combustion chamber —2— and water jacket or chamber —3— surrounding the fire box and adapted to be connected to water circulating pipes —4— forming a part of a heating system. The water chamber —3— is closed at the top by a partition wall —5— having a central opening —6— therethrough communicating with the combustion chamber —2—. The boiler is also provided with a 60 hollow top section —7— having a smoke chamber —8— provided with a draft or outlet port —9— and a check port —10—, the draft port —9— being adapted to be connected to a suitable chimney or smoke stack 70 not shown, while the check port —10— is provided with a check damper or valve —11— hinged at its upper edge at —12— to the top wall of the section —7—. The top of this section —7— which is preferably flat is 75 formed with a central opening —13— having a lid or closure —14— fitted therein and normally closed but provided with a central aperture —15— for receiving a vertically 80 movable rod —16—.

The opening —6— in the upper end of the fire box or combustion chamber —2— is provided with a movable closure or disk valve —17— having a central aperture —18— through which the rod —16— is loosely extended. Secured to the lower end of the rod is a shoulder —19— somewhat larger than the aperture —18— so as to engage and lift the disk valve —17— when the rod is elevated beyond a predetermined degree in 90 a manner hereinafter described.

The check valve or damper —11— is provided with an inwardly projecting arm —20— rigidly secured thereto below the pivot —12— and having its inner end projecting into the path of movement of an operating member —21—, which, in this instance, consists of a circular disk adjustably secured to the rod —16— within the chamber —8— or between the disk valve —17— 100

and top of said chamber, said operating member —21— being held in its adjusted position by means of a set screw —22— and is adapted to engage the arm —20— to open the check valve —11— when the rod is moved downwardly to a predetermined position.

The valve operating rod —16— extends some distance upwardly above the boiler and 10 is pivotally connected at its upper end to one end of a lever —23— which in turn is fulcrumed at —24— intermediate its ends upon a bracket —25— on one side of an expansion tank or water column —26—. This 15 expansion tank or water column —26— is open at the top and has its lower end connected by a pipe —27— to one of the pipes —4— of the hot water circulating system.

A float —28— is movable in the expansion tank or water column —26— and is 20 adapted to rest upon a body of water —29— therein, the upper end of the float being connected by a rod —30— to the corresponding end of the lever —23— which is 25 weighted at —31— to partially counterbalance the weight of the rod —16— and parts carried thereby, and at the same time rendering the operation of the float and valves more sensitive under varying levels of the 30 column of water —29— by expansion and contraction.

The shoulder —19— and disk —21— are 35 adjusted relatively to each other and to the arm —20— and disk valve —17— so as to open the disk valve —17— and simultaneously permit the check valve —11— to close.

It is now evident that as the temperature of the water in the boiler and circulating system including the water column —26— 40 varies above and below a predetermined degree, the water level in the column will rise and fall, so that when the temperature of the water is below such predetermined degree, the receding level of the water in the column —26— will allow the float to descend by its own gravity aided by the weight —31— to lift the rod —16— and disks —21— and —17— carried thereby sufficiently to lift the disk valve —17— from 45 its seat upon the upper end of the combustion chamber —2— and at the same time withdrawing the disk —21— from holding engagement with the arm —20— and allowing the check valve —11— to close under its 50 own weight as shown in Fig. 3. This opening of the disk valve —17— places the combustion chamber in direct communication with the draft port —9— thereby increasing the combustion of the fuel in the 55 combustion chamber —2— and raising the temperature of the water. Now, if the temperature of the water should be raised beyond the predetermined degree mentioned, the expansion of the water column —29— 60 would raise the float —28— and thereby

lower the rod —16— sufficiently to cause the disk valve —17— to close upon its seat on the upper end of the combustion chamber while the disk —21— would also engage the arm —20— and open the check valve —11— 70 to establish direct communication between the draft port —10— and atmosphere and cut off communication between said draft port and combustion chamber. This latter operation would, of course, retard combustion and cause the temperature of the water to be lowered and to recede in the expansion tank —26— thus permitting the float to again descend and produce a repetition of the operation of the draft and check valves 80 previously described. If for any reason the temperature of the water should continue to rise after the disk valve —17— is closed, it is evident that the increased expansion of the water would cause the float to rise 85 still farther which in turn would cause the rod —16— to slide downwardly through the disk valve —17— to further open the check valve —11— and thereby additionally check the fuel from increasing combustion. 90 The effect, therefore, of these combined actions of the float and valves controlled thereby is to maintain a uniform temperature of the water in the circulating system and thus establish a uniform temperature 95 of the room or compartment in which a portion of this system may be installed.

It will be observed upon reference to the drawings that the opening —13— in the top of the boiler is of sufficient size to permit the rod —16— with the disks —21— and —17— thereon to be readily withdrawn without disturbing the check damper —11— and that the float may also be withdrawn through the upper end of the expansion tank —26— by simply removing the pivotal bolt or pin —24— of the lever —23—. It will also be observed that by changing the position of the disk —21— above or below that indicated in the drawings the check valve —11— will be opened accordingly later or earlier in the movement of float thereby permitting the temperature which it is desired to maintain to be raised or lowered at will. The disk valve —17— may also be adjusted lengthwise of the rod by the threaded shoulder or nut 19 for the same purpose.

What I claim is:

In combination with a hot water heater 120 having a combustion chamber, a water chamber, a smoke chamber communicating with the combustion chamber, said smoke chamber having a check damper in one side thereof provided with an inwardly-extending arm, a valve controlling communication between the combustion chamber and smoke chamber, a vertically-movable rod slidably passed through said valve and provided with means to lift the valve from

its seat during the upward movement of the rod, a check valve operating member adjustably mounted on the rod for engaging said arm and operating the check valve in a downward movement, a water column connected to the water chamber of the heater, a float in said column, and means actuated by the float for operating the rod.

In witness whereof I have hereunto set my hand on this 15th day of June 1911.

WILLIS A. SCHLEIT.
